[57] CLAIM

[21] Appl. No.: 776,129

The ornamental design for a vehicle body, as shown and described.

DESCRIPTION

FIG. 1 is a side elevational view of a vehicle body showing our new design.

FIG. 2 is a top plan view.

FIG. 3 is a rear elevational view.

FIG. 4 is a front elevational view.

FIG. 5 is a front top perspective view, and

FIG. 6 is a rear quarter perspective view.

The broken lines in the drawing are for illustrative purposes only and form no part of the design claimed.
